UNITED STATES PATENT OFFICE.

JOHN B. BELCHER, OF CHARLOTTE, MICHIGAN.

OVERSHOE OR ARCTIC.

SPECIFICATION forming part of Letters Patent No. 296,115, dated April 1, 1884.

Application filed December 21, 1883. (No model.)

To all whom it may concern:

Be it known that I, JOHN B. BELCHER, a citizen of the United States of America, residing at Charlotte, in the county of Eaton and State of Michigan, have invented certain new and useful Improvements in Rubber or Cloth Overshoes or Arctics, of which the following is a specification, reference being had therein to the accompanying drawings.

10 My invention pertains to an improvement in rubber or cloth overshoes or arctics; and it consists in lacing hooks and eyelets designed therefor, in the peculiar construction thereof, the method of securing the hooks and eyelets in position; and in the construction, combination, and arrangement of the parts, substantially as hereinafter more fully set forth and claimed.

15 In the accompanying drawings, Figure 1 is a perspective view embodying my improvement. Fig. 2 is a plan view of the fastening-cloth, and Figs. 3 and 4 are detail views.

The lacing hooks and eyelets may be made out of bent wire, or struck out of sheet metal, 20 in any well-known manner. The lacing-hooks A each have, excepting the one at the upper part of the shoe, the center bar, *a*, Fig. 3, the two corresponding arms *b* projecting at right angles to it, and the hooks *C*, arranged outside the edge of the material of the shoe, and 25 projecting back toward the center bar, *a*, as shown; and these are designed for reception of a lacing-string for lacing the shoe, the string being held by the hooks and laced therein in 30 the manner which ordinarily obtains in lacing-shoes having eyelets. The lacing hook and eyelet *B*, at the upper part of the shoe, is constructed in manner and form similar to those 35 designated by the letter *A*, with the exception that its upper end, *b*, terminates in the eye *e*, Fig. 4, which is designed for making fast therein the lacing-string, in order that it may al-

ways be in readiness to hook and tie therein. The lacing hooks and eyelets *A* and *B* are each formed of a **U**-shaped piece of wire. The 45 hooks and eyelets are applied with cloth arranged thereon, as shown in Fig. 3, and between the lining and the outer part of the shoe. The method of securing them to the shoe is illustrated in Figs. 2 and 3. 50

Fig. 2 represents a square piece of cloth, which is folded on the dotted line *F*, and then applied to the body of the hook and eyelet, as shown in Fig. 3. The hooks and eyelets, respectively, are secured by the pieces *E*, and 55 additionally secured by the auxiliary supporting-pieces *D*, which are fitted between the arms *B*. This method of securing the hooks and eyelets prevents their possible removal by the strain to which they are ordinarily subjected. They are attached to the shoe between the lining and the outer part thereof with cloth or rubber fabric so prepared as firmly to adhere thereto in process of vulcanization, as it is not practicable to use an ordinary eyelet in 60 connection with rubber shoes. 65

Having described my invention, what I claim is—

1. In a rubber, cloth, or arctic overshoe, the **U**-shaped piece of wire *A*, having center bar, 70 *a*, and hooks *C*, for the reception of the lacing-string, substantially as shown, and for the purpose described.

2. In a rubber, cloth, or arctic overshoe, the lace hook and eyelet consisting of the **U**-shaped 75 piece of wire *B*, having center bar, *a*, eye *e*, and hook *C*, substantially as shown, and for the purpose described.

In testimony whereof I affix my signature in presence of two witnesses.

JOHN B. BELCHER.

Witnesses:

JOHN C. FILE,
L. O. SMITH.
